JACOB REESE, OF PITTSBURG, PENNSYLVANIA.

Letters Patent No. 65,832, dated June 18, 1867.

IMPROVEMENT IN MACHINES FOR STRAIGHTENING CYLINDRICAL BARS OF METAL.

The Schedule referred to in these Letters Patent and making part of the same.

TO ALL WHOM IT MAY CONCERN:

Be it known that I, JACOB REESE, of Pittsburg, in the county of Allegheny, and State of Pennsylvania, have invented a new and useful Improvement in Rolling and Straightening Cylindrical Bars and Tubes of Iron, Steel, or other metals; and I do hereby declare the following to be a full, clear, and exact description thereof, reference being had to the accompanying drawings, making a part of this specification, in which—

Figure 1 is a perspective view of the devices I employ; and

Figure 2 is a top view thereof, a part of the framework being removed.

Like letters of reference indicate like parts.

The mode of rolling or forming cylindrical bars or shafts formerly in common use, was to run such bars or shafts through between the opposite surfaces of cylindrical rolls, in the faces of which grooves were cut, of the shape sought to be given to the bar or shaft. This mode of rolling, however, had a tendency to flatten the bar, so as to make its cross-section somewhat of an elliptical shape. The bar was then turned so as to bring the major axis of such cross-section at right angles to the axis of the rolls, and the rolling continued till the bar was made as nearly cylindrical as was possible by that process. As improvements on this method, such bars or shafts have been rolled between the converging surfaces of parallel rolls, or between the cylindrical surfaces of rolls whose axes were slightly inclined to each other, or between the opposite surfaces of rolls hollowed or grooved, the direction of the bar so rolled generally being parallel, or nearly so, to the axis of one or both the rolls so used. In the two modes of rolling last named, the tendency of the process is to tear open the welds of the iron, or lessen the adhesive qualities of the particles composing the cylindrical surface of the bar or shaft. The difficulties attending all these modes of rolling are overcome, to a great extent, if not wholly, by my invention, which consists in rolling cylindrical rods, bars, and shafts, and in straightening cylindrical tubes or pipes of iron, steel, or other metals, between the conical faces of revolving disks, or the conical ends of revolving rolls, such disks or rolls revolving opposite to each other and in opposite directions, and in the devices by which such rolling or straightening is to be done.

To enable others skilled in the art to make and use my invention, I will proceed to describe its construction and mode of operation.

The materials I employ in the construction of my machinery are such as are ordinarily used, or are adapted to the purposes hereinafter to be mentioned. A is a bed, frame, or foundation on which the main part of the machinery rests. The upright posts B B and cross-bar C constitute a hanging frame for the shafting, though usually I find it better to attach such shafting to the building above, as is now commonly done. On the plumber-blocks *a a*, and resting in proper bearings, *a' a'*, is the axle *b*, to which power is applied by a crank, or by other such gearing as is ordinarily used for communicating motion. On the axle *b* is a pulley, *c*, and rigidly attached to its inner end is the vertical disk-roll *d*, having a face slightly conical, as shown in fig. 2. By the pulley *c* and belt *b* motion is communicated to the corresponding pulley *c'*, and its shaft *f*, which latter operates the universal joint *g*, and through it the shaft *f'* and pulley *h'* hung thereon. The pulleys *c'* and *h'*, with their shafts *f* and *f'*, are supported in any convenient manner by the hanging frame B C, and operate in boxes inserted therein or attached thereto; or, as just mentioned, they may be supported from the building above. From the pulley *h'* motion is reversed by the cross-belt *l*, and communicated to the pulley *h*, which, with the disk-roll *d'*, is attached to the axle *b'*, operating in boxes or bearings *m' m'*, which rest in the plumber-blocks *m m*. The disk-roll *d'* has also a conical face similar to that of the disk-roll *d*. Between the disk-rolls *d* and *d'*, and with its axis usually a little below the centre of the lower one of such rolls, is the cylindrical rest-roller *n*, of a diameter somewhat less than the distance between the faces of the disk-rolls *d d'* in their line of bite. It is placed on bearings *o' o'*, which are set on or in the plumber-blocks *o o*. The bearings *o' o'* may be removed, and larger or smaller ones inserted, in order to raise or lower the rest-roller *n*, when necessary, or other well-known mode of adjustment in lieu thereof may be substituted. Resting on this rest-roller *n*, and playing on and along its surface, is the rod, bar, shaft, or tube *z*, which is to be rolled or straightened. The axle *b'* is so fitted to its bearings *m' m'* that the disk-roll *d'* may be adjusted to operate nearer or more distant from the corresponding disk-roll *d*. This adjustment I effect by making a socket in the outer end of the axle *b'*, in which to operate the end of a screw, *p*. The plumber-block *q* carries a box or nut in its upper end, which is tapped for the thread of the screw *p*. By turning up or slackening the screw *p* by its head *p'*, the disk-roll *d'* is moved up towards or allowed to recede from its corresponding roll *d*, the axle *b'* sliding in its bearings for that purpose, as above indicated. The disk-rolls *d* and *d'* are thus made to bite the bar *z* with a sufficient degree of compression to give it a rotary and also a forward movement as hereinafter to be described. The faces of the disk-rolls *d d'* are made of conical shape, as already indicated, the altitudes of the cones thus formed usually

being small in proportion to the diameters of their bases respectively, which latter are equal, or nearly so, each to the diameter of its own disk-roll. The apexes s s' of the cones thus formed may be slightly rounded, if so desired, though commonly I bring them to a point. It is also practicable to make such faces of the shape of the frustum of a cone, though seldom, if ever, desirable. The object in view in giving the faces of the disk-rolls d d' a conical shape, is to make the line of their bite lie entirely on one side of the apexes s s' , and not exceed in length the distance from either apex s or s' to the periphery of its own roll d or d' ; for if the faces of the disk-rolls d d' were flat, and the line of bite extended across on both sides of their centres, the action of the disk-rolls d d' , in the line of bite on one side of their centres, would obviously be opposed to their action on the other side, so that no valuable result could in such case be secured. The plumber-blocks m m are usually of less altitude from the foundation A than the corresponding blocks a a , so as to bring the axis of the axle b' and the apex s' of the conical disk-roll d' out of the line of, or below the apex s of the corresponding disk-roll d . It is not necessary, however, that the apexes s s' be in the same vertical plane, only that the plane passing through them be at right angles, or nearly so, to the direction of the forward or longitudinal motion, which is to be given to the bar or tube z which is to be rolled or straightened. The line of bite of the disk-rolls d d' against the bar or tube z should, to secure the most perfect action possible, be in a plane passing midway between such centres or apexes s s' , in which case both disk-rolls, the one, d , working with a downward motion on a line of bite below its centre or apex s , and the other, d' , working with an upward motion on a line of bite above its apex s' , will, on the well-known principle of "resolution of forces," impart to the bar or tube z not only a rotary motion on its axis, but also, and at the same time, a forward motion in the line of its axis. But the line of bite need not be necessarily in a plane passing exactly midway between the apexes s s' , as described, since it may be either above or below such plane, though the greater its distance above or below, the less smoothly and satisfactorily will the machinery as above described operate. The vertical distance between the two apexes s s' need not be great, but the greater it is, other things being equal, the more rapid will be the forward or longitudinal motion of the bar z , and *vice versa*. I am thus enabled so to adjust the forward motion that the bars or tubes z shall be passed through between the disk-rolls d d' as fast as they are reduced to the required cylindrical form. But in order to secure a bite such as that described, it is necessary to adjust the machinery so that the opposite faces of the disk-rolls d d' , on one and the same side of the apexes s s' , shall be parallel, or nearly so. This I do by so adjusting the axle b' on its bearings that it will make, with the prolongation of the axis of the axle b , an angle equal to the sum of the angles of elevation of the sides of the cones forming the faces of the disk-rolls d d' . The opposite faces of the disk-rolls d d' , on the same side of their apexes s s' , and along their line of bite, will then be approximately parallel; so much so as to secure the rotary and forward movements as above described. Of course the shafting f f' must be hung parallel to the axles b b' , respectively, and hence the necessity of the universal joint g , or such bevel-gearing in lieu thereof as will secure the same result. But in order to make the bar or tube z move through between the disk-rolls d d' , along and resting upon the upper surface of the rest-roller n , I usually make one of the pulleys c' of a diameter slightly larger than that of its corresponding pulley h' , or otherwise vary the relative size of the gearing employed, so as to give to the disk-roll d' , having an upward motion on its line of bite, a slower revolution than is given to the disk-roll d , working with a downward motion on its line of bite. In such case the more rapid motion of the disk-roll d will carry the bar or tube z , if it chances to be inserted at or near the top of the rolls, downwards on to the rest-roller n , and prevent its rising above that line of bite as the process of rolling goes on.

The bar to be rolled being heated to any desirable temperature, one end of it is inserted between the peripheries of the disk-rolls d d' , the other end, if necessary, being supported in any convenient manner. Then, by operating the devices described, and in the manner above stated, I communicate to the bar so inserted a rotary motion on its axis, by which to give it a cylindrical shape, as it passes through along the line of the bite of the disks d d' , such forward motion being in the line of its axis, and being also communicated to it at the same time with the rotary motion above described. I apply the devices described to shaping, rolling, or straightening cylindrical rods, bars, shafts, tubes, and pipes of any metal or metallic compound, the mode of operation being in all cases substantially the same and as above described.

What I claim as my invention, and desire to secure by Letters Patent, is—

1. Rolling and straightening cylindrical rods, bars, shafts, and tubes, or pipe of iron, steel, or other metals, between the conical faces of revolving disks, or the conical ends of revolving rolls, arranged substantially in the manner and for the purposes above set forth.
2. The pair of revolving cone-faced disks, arranged as described, so as to revolve in opposite directions, having their axes of revolution inclined so as to bring their operative faces, forming the bite of the disks, parallel to each other, and having their axes in slightly different planes, for the purpose of giving a combined rotary and forward motion to the metallic rod, bar, shaft, or tube, held between the bite of the disks, substantially as described.
3. The combination of a pair of rolls or disks, d d' , having conical ends or faces, with the rest-roller n , arranged and operating substantially as hereinbefore described.
4. The combination of the screw p with the axle b' and disk or roll d' , for the purpose of increasing or lessening the distance of the disk or roll d' from its corresponding disk or roll d , substantially as above described.

In testimony whereof I, the said JACOB REESE, have hereunto set my hand in presence of—

JACOB REESE.
